UNITED STATES PATENT OFFICE.

THOMAS MATHEWS, OF LEICESTER, ENGLAND; ANNIE MATHEWS AND HENRY W. BUCKINGHAM EXECUTORS OF SAID THOMAS MATHEWS, DECEASED.

CARDBOARD AND LIKE TOYS.

1,403,515.

Specification of Letters Patent. Patented Jan. 17, 1922.

Application filed July 15, 1920. Serial No. 396,497.

To all whom it may concern:

Be it known that I, THOMAS MATHEWS, subject of the King of Great Britain, residing at Leicester, in the county of Leicestershire, England, have invented certain new and useful Improvement in or Relating to Cardboard and like Toys, of which the following is a specification, reference being had therein to the accompanying drawing.

10 This invention relates to toys and is particularly though not exclusively applicable to those made out of cardboard or similar light material.

15 The invention refers to toys in imitation of human figures, and the present improvement comprehends as its chief object the production of a puppet in cardboard embodying the characteristics of the puppet which most ventriloquists employ as an essential accessory to their performances, and as will be obvious, the invention is particularly adapted for use by young children.

20 The invention includes a puppet in cardboard or the like fashioned and printed to represent a human being, say a boy for example, and the improvement is particularly directed to the mouth and eyes.

25 It is a specific and important feature of the invention to provide the puppet with a movable mouth and eyes connected to a finger piece at the back of the figure which can be actuated by the finger or thumb of the manipulator to effect movement of the mouth and eyes and vary the facial expression of the puppet.

30 In particularly describing the invention reference will be made to the accompanying drawings wherein a cardboard toy constituting a practical example of the invention 40 is illustrated.

In the drawings:—

Figure 1 is a front view of the toy.

Figure 2 is a back view, and

Figure 3 is a side view of the same.

45 Figure 4 is a perspective rear view of the upper part of the toy drawn to a larger scale.

Figure 5 is a front view of the movable member detached from the toy.

50 Throughout the drawings like parts are designated by the same reference characters.

In the illustrated example the toy com-

prises a body part 1 cut out of cardboard, thighs 2 made of flexible or woven material, and feet and leg members 3 of cardboard. 55 The material 2 is secured to the parts 1 and 3 by adhesive and enables the figure to be placed in a sitting attitude (such as on a table or the operator's knee) with the legs suspended in imitation of a ventriloquist's puppet.

Formed in the part 1 are openings 4 and 5 (Figure 1) for the mouth and eyes respectively, and at the back of said part is a movable member 6 (Figures 2, 3 and 4) 65 upon the front of which, as indicated in Figure 5, a part of the mouth viz., the chin and lower lip and teeth, and also the eye pupils are portrayed.

This movable member 6 has formed in it 70 a central vertical slot 7 which fits upon a shorter projecting piece 8 (Figures 2 and 4) fixed upon the back of the part 1 the member 6 being kept in place upon the piece 8 by a cover 9 secured to the piece 8 and 75 extending over the back of the member 6. As shown in Figure 3 the member 6 is situated between the part 1 and the cover 9, it being understood that the said member is so fitted upon the piece 8 as to be capable of 80 free movement up and down thereon said piece serving as a guide for the member. The ends of the slot 7 by contact with the ends of the piece 8 limit the movements of the member 6.

85 Conveniently the movable member 6 has two sets of eye pupils in different relative positions or angularly disposed as shown in Figure 5. Upon the member 6 being moved downwards the mouth is opened and the 90 upper set of pupils are brought into view behind the openings 5 and, as indicated in Figure 1, appear at the ends or corners of their sockets. Upon the member 6 being moved upwards, the mouth is closed and the 95 other i. e. the lower set of pupils come into a central position behind the openings 5. Thus by manipulating the slideable member 6 the mouth is given the appearance of opening and closing, as in talking, and at 100 the same time the eye pupils appear to move sideways which combined movements produce a realistic change of expression.

Attached to the movable member 6 is a

finger piece 10 (Figures 2, 3 and 4) arranged when in use to stand away from the back of the said member so that the operator's forefinger may be inserted in a hole 5 11 for moving the part 6 up and down.

Below the member 6 and finger piece 10 thereon, the figure 1 is furnished at the back with a projecting member 12 adapted to be held by the thumb and finger for which purpose, and in order that it may be firmly gripped upon opposite sides, points 13 are provided.

The finger piece 10 and holder 12 are scored or hinged at the corners so that they 15 can fold and be pressed flat to the back of the figure for packing purposes. To keep the lower part of the member 6 close up to the back of the figure, a piece of card-board 14 is fixed so as to extend upwards over 20 the said member as shown in Figures 3 and 4. The member 6 works underneath this piece 14.

In using the toy the figure is held by gripping the member 12 upon opposite 25 sides by the thumb and second finger while the member 6 operated by the forefinger inserted in the hole 11, is moved as aforesaid to effect the variations of the expression as may be required.

30 The parts 1, 3 and 6, are painted or printed on the front in an appropriate manner to represent the desired features and other parts of the individual. The invention may be similarly applied to representations of animals, birds, and the like. In the 35 example illustrated, the complete toy is, with

the exception of the thighs 2, made of card-board.

What I claim then is:—

1. A puppet toy comprising a flat figure 40 having eye and mouth openings therein, a guide on the back of said figure, a flat member slideable on said guide and having eyes and a mouth thereon for exhibition behind said openings, a projecting finger piece on 45 said member for operating the same, and a projecting holding piece on the back of the figure by which the latter may be held, said finger piece and holding piece being constructed to fold to a flat condition. 50

2. A puppet toy comprising a flat cut out figure having eye and mouth openings therein, a guide on the back of said figure, a flat member slideable vertically on said guide and having eyes and a mouth thereon for 55 exhibition behind said openings, a cover attached to said guide and overlapping the slideable member to retain the latter in position on the guide, a four-sided hinged structure on the back of the slideable member, 60 said structure having a hole therein for the insertion of the operator's finger, and a four-sided hinged structure on the back of the figure adjacent the aforesaid structure and adapted to be held by the thumb and 65 fingers for carrying the toy during use.

In testimony whereof I affix my signature in presence of two witnesses.

THOMAS MATHEWS.
